COMBINATION GRAIN BINDER AND
SHOCKER

James A. McElroy, Kansas City, Mo.

Application December 29, 1937, Serial No. 182,326

10 Claims. (Cl. 56—403)

This invention relates to a combination grain binder and shocker, the present application being a substitute in part for an application filed by me on November 12, 1925, Serial No. 68,580.

5 The principal object of the invention is to provide an inexpensive, durable, and efficient combination grain binder and shocker to cut grain, bind the grain into sheaves, form the sheaves into shocks, and deposit the shocks upon the ground 10 with the heads of the grain upstanding so that the shocks may be subsequently gathered for threshing.

Other objects of the invention are to provide 15 means for tying the shocks before depositing them on the ground; to provide means for dropping one or more sheaves to the ground for use as caps; to provide means on the binder to determine sheaves while the shocker is depositing a formed shock; and to provide means for controlling tension on the twine with which the shock 20 is tied.

In accomplishing these and other objects of the invention, as hereinafter described, I have provided improved details of structure, the preferred 25 form of which is illustrated in the accompanying drawings, wherein:

Fig. 1 is a perspective view of a combination grain binder and shocker constructed in accordance with the present invention.

30 Fig. 2 is a perspective view of the combination grain binder and shocker as viewed from the shocker side, the parts of the shocker being in position to receive sheaves from the binder mechanism.

35 Fig. 3 is a similar view showing the parts of the shocker in tripped position for setting a shock.

Fig. 4 is a detail view of the double acting crank-arm and trip stop.

40 Fig. 5 is a detail view of the mechanism for holding a bundle while the shocker is being actuated to deposit a shock.

Fig. 6 is a view of a portion of the shocker from the side next to the binder showing the sickle, 45 sickle pitman shaft, shock knotted head, knotted shaft and arm, sprocket and clutch, trip drop, the upender, and initial and fast speed means.

Fig. 7 is a perspective view of the upender slow and fast speed mechanism.

50 Fig. 8 is a view of the trip dog.

Fig. 9 is a detail view of a portion of the front end of the shocker showing the sprocket, clutch, trip dog, trip dog stops, and compressor.

Fig. 10 is a similar view showing a different 55 position of the trip dog.

Fig. 11 is a perspective view of the front elevator framework.

Fig. 12 is a perspective view of the main frame.

Fig. 13 is a detail perspective view of the twine tension and release mechanisms.

Fig. 14 is a detail perspective view of the conveyor and lower elevator.

Fig. 15 is a perspective view of the knotter head, tier wheel, and breast plate.

Fig. 16 is a perspective view of the bundle drop 10 mechanism for providing shock caps.

Fig. 17 is a perspective view of the swinging universal joints and shafts of the tower drive whereby the various mechanisms are operated directly from the power take-off of a tractor.

Referring more in detail to the drawings:

The grain cutting and binding portion of the machine is of conventional construction and may be briefly described as including a grain platform 1 carried by a main wheel 168 and a grain wheel 20 170. Supported on the front of the platform is a sickle 3 for cutting the grain which is transferred by a conveyor 2 to an inclined binder deck 5 which is supported over the main wheel and carries the sheaf forming and tying mechanism, 25 later described. The main wheel 168 is carried in standards 184 and 185 on the binder frame 186 and cooperates with the grain wheel in supporting the platform. The binder also includes the usual 30 reel, operator's seat and platform tilting lever, the operator's seat being carried on the goose-neck support 176. The bundle carrier of a conventional binder and its associated parts, however, are eliminated and substituted by the shocker mechanism as later described.

35 The conveyor 2 is of the ordinary slat and canvas type carried by side chains 144 and 145 which rotate over sprockets 147—148 idling upon a shaft 146 carried at the grainward end of the platform, the sprockets being retained in spaced position by 40 keys 149 and 149' as shown in Fig. 14. The opposite ends of the chains operate over sprockets 155 and 156 fixed to a shaft 159 supported by the harvester frame adjacent the upper portion of the binder deck 5. The section of the conveyor 45 operating over the platform is retained in horizontal position by guide plates 150—151 and rollers 152—153 carried by the front and rear sills of the platform, the rollers being retained in suitable bearings by spring cotters 154 as shown 50 in Fig. 14. From the rollers 152 and 153 the conveyor inclines upwardly to discharge the grain onto the binder deck with the aid of a roller 6. Cooperating with the inclined portion of the conveyor is an upper conveyor 4 driven from a gear 55

179 meshing with a gear 157 on the shaft 159. The roller 6 is also driven from the gear 157 by a gear 158 meshing therewith and fixed to the roller shaft 6 as shown in Fig. 14. The reel of the binder is also driven from the shaft 159 through miter-gears 180 and 181 which are connected with the customary reel operating connections (not shown).

The shaft 159 is driven by an endless chain 160 (Fig. 1) operating over a sprocket 188 on the rear end of the shaft 159, a sprocket 187 for operating the tying mechanism, over a driving sprocket 161 which is fixed to a pitman shaft 35 journalled in the frame 186, and over a tightening sprocket 162 as shown in Fig. 1. Fixed to the pitman shaft is a miter-gear 183 meshing with a miter-gear 187 on a counter-shaft 164 which is driven from a sprocket 163 on the main wheel 168, through a chain 166. It is thus obvious that the platform conveyor, upper conveyor 4, reel, sheaf forming mechanism, and roller 6 are all driven from the main wheel incidental to movement of the machine along the field.

The pitman shaft 35 carries a pitman wheel 35' to operate the sickle 3 through a pitman 3'. The grain delivered to the binder deck gravitates onto packers 7 cooperating with a butterboard 8 to convey the grain against compressor springs 10, 11 and 11' and a trip 9 which sets the tying mechanism into action to tie the grain into sheaves which are discharged by arms 12 into the shocker mechanism.

The shocker includes a frame rigidly attached to the binder frame 186 and includes side bars 15, 16, 17, 18 and 19, a front cross bar 20, a rear cross bar 21 and upright bars 23, 45, 46 and 85. The shocker includes an upender 13 and a butt holder 14. The shock upender is of substantially U-shape, carried by a substantially U-shaped shaft-like member 25 having lateral ends 26 and 27 rotatable in suitable bearings on the frame bars 15 and 16 respectively. The shaft end 27 projects through its bearing on the bar 16 and has its free end mounted in a bearing on the bar 17 which is connected to the bar 16 by the bar 19 as shown in Fig. 17. The upender also includes a shock settler 36 that is connected to the top of the upender at 37 and 38 and at the bottom by a spring 39, the spring 39 being connected at one end to the upender as at 40, and at its other end to the shock settler as at 41.

The butt holder 14 is carried on a shaft 42 at the front end of the shocker frame and journalled in bars 45 and 46 which depend from the front cross bar 20, the shaft 42 having rearwardly extending arms 43 and 44 supporting the butt holder 14. Hinged to the crank-arm 44 is a link 47 hinged at its upper end to a lever 49 which is pivotally mounted on the bar 15 as at 50. Connected with the lever 49 is a chain 51 having its other end connected to a double acting crank-arm 53, as at 54, the crank-arm 53 being pivotally attached to a crank-arm 59 on the shaft end 26 to thus connect the upender with the butt holder. Hinged on the side bar 15, as at 56, is a trip stop lever 55, adapted to retain the shock holder home when a shock is being formed. The trip stop 55 has a retracting spring 57 (Fig. 4), fastened at one end to the trip stop lever and at the other to the bar 15. The crank-arm 53 hinges one way about the center of the crank-arm 59 and engages under the stop lever to support the upender and butt holder in position to receive sheaves from the binder, but the levers 53 and 59 are released so that the butt holder

swings to drop the butt of a shock to the ground and the upender is free to turn and cooperate with forward travel of the machine in upending a formed shock. While the upender is making about the first quarter turn, or when the shock is on end, a fast speed mechanism automatically comes into play and speeds up the upender so that the upender is rotated at a fast speed to clear the upended shock. This mechanism includes a bevelled gear 28 and an interconnected clutch wheel 29 loosely mounted on the end 27 of the shaft 25 (Fig. 7). The bevelled gear 28 is rotated by an intermeshing bevelled gear 30 on a shaft 31 journalled in suitable bearings attached to the bar 19 and which is driven by a sprocket 32 fixed on the shaft and actuated from a sprocket 34 on the pitman shaft 35 by an endless chain 33 operating over the respective sprockets.

Cooperating with the clutch wheel is an arm 58 fixed to the shaft end 27 and hinged thereto, as at 64, is a trip dog 63, having a toe 63' adapted to engage teeth of the clutch wheel 29 and connect the shaft 29 in driving relation with the clutch wheel. The toe of the trip dog is normally urged toward engagement with the teeth of the wheel 29 by a spring 58' fastened to the toe of the trip dog and to the arm 58. The trip dog, however, is kept from engagement with the teeth until the upender has set the shock upon the ground, since the tail portion 65 of the trip dog rides upon an arcuate track 60 fixed to the bar 19.

In order to control the point where the tail of the trip dog rides off the track to make the fast speed drive effective, the track preferably includes a section 60' having a lateral arm 62 pivotally connected as at 60' with a bracket 61 secured to the bar 16 as at 61'. The arm 62 is engaged by a roller 69 carried on a crank-arm 68 having a shaft portion journalled in bearings 67 fixed to a depending arm 22 of the rear cross bar 21 and which terminates in a laterally extending finger 66 adapted to be engaged by a deposited shock to swing the section of the track 60' out of engagement with the tail 65 of the trip dog 63, at which time the spring 58 draws the toe 63' into clutching engagement with the teeth of the wheel 29, whereupon the shaft 25 is driven at the speed of the clutch wheel to accelerate movement of the upender so that the upender gets away from the shock, leaving the heads of the grain upstanding.

The crank-arm preferably includes sections connected by a sleeve 68' secured by set-screws 69' whereby the effective length of the arm may be varied so that the finger 66 may be caused to trip sooner or later. The arm 68 is retained in retractive position with respect to the lever 62 by a spring 70 connecting the arm 68 with the bar 18 and the track extension 60 is normally retained in registry with the fixed track section by a spring 70 which connects the arm 62 and the bar 16.

Mounted on the shocker frame is a tier attachment by which a string is tied around a shock prior to deposit of the shock on the ground (see Figs. 1, 2, 3, 9, 10 and 15). The tier attachment includes an oscillatory needle shaft 100 extending along the side bar 15 of the shocker frame and having its forward end mounted in a bearing 101' carried on the bar 20 and at its rear end in a bracket 102'. The needle shaft has a crank-arm 101 at its forward end and a needle 102 at its rear end. Carried on the free end of the needle is a twine guide and a twine 75

hold-down 103 to hold the twine in proper position while tying a large shock. The twine 112 is carried in a container 104 attached to the bar 46 and extends from the container through a tension mechanism 106 (see Fig. 13), attached to the side bar 15. The tension mechanism 106 includes a tension member 113 having an arm 107 pivoted thereto as at 109, which arm carries a roller 108 cooperating with the tension part 113 to tensioningly engage the twine 112. The roller 108 is adapted to be retained in tensioning position with respect to the part 113 at predetermined times by a spring 110 on a tensioning bolt 109 whereby the spring is adjusted to put the proper tension on the twine when needed.

In order to selectively release tension on the twine, the lever 107 is connected by a spring 111 with a finger 114 fixed to the needle shaft 100 so that tension on the twine is released when the shaft moves in one direction and is established when the needle shaft moves in the opposite direction. From the tension mechanism the twine extends through a take-up 115 to the hold-down 103 and through the needle eyes 116 and 117 into the twine disk 82. The knitter shaft 71 (see Figs. 6, 9 and 10), is parallel with the needle shaft on the opposite side of the shocker frame and the front end is mounted in a bearing on the upper end of the bar 45 and the opposite end thereof is mounted on the upright end of a bar 35 fastened to the center of the bar 19 and at its lower end to the binder frame 106. The knitter shaft 71 has a crank-arm 72 and a knitter head 76 on the other end, the shaft being rotated by a chain 141 operating over a sprocket 13 on the shaft which is adapted to be connected therewith by a clutch 74. Cooperating with the clutch is a trip dog 75 which hinges on a trip dog casting 93 (Fig. 8), the casting 93 being fastened solidly on the knitter shaft 71. The trip dog 75 has a roller 94 and a push spring 95 which works between the trip dog 75 and the trip dog casting 93 to lock the roller 94 into the clutch teeth 96 of the clutch (Figs. 9 and 10). The crank-arm 72 is connected to the needle shaft crank-arm 101 by a link 97. The trip dog stop illustrated in Figs. 9 and 10, consists of a trip stop member 98 to which is attached trip stops 87, 88 and 89'. The stop member 98 hinges on supports 90 and 90' and has a pull spring 98', the supports 90 and 90' being fixed to the cross bar 20. Pivoted on a support 91' is a manually actuated trip stop 89 having a crank-arm 89' that is connected with a cable 99 leading to the operator's seat on the binder so that the cable may be operated to trip the dog 75 to tie a shock whenever desired. When the trip stop 89 is tripped, the dog 75 contacts the automatic trip stop 98 and on discharging the next bundle it is automatically tripped to tie the shock. The trip dog stop member 98 is rocked automatically each time a sheaf is discharged from the binder. This is effected by a link 118 connected at one end to the binder discharge crank-arm 119 (Fig. 2), and at the other end has a bias slot 120 working on a pin 121 at the upper end of the support 90'.

Under the side bar 15 is a shock compressor member consisting of a pipe 122 hinging on the side bar 15 at 123. The front end of the pipe 122 is connected at 126 with a link 124, the other end of the link 124 being connected to the link 97, previously described, as at 125, so that when the needle moves down while tying, a compressor member 127 fixed to the pipe 122 will

compress the shock. This compression will be relieved when the needle is returning to its original position.

The upender trip 55 is released by a cable 128 which is secured to the trip stop 55 and extends through a pulley 130 and is connected with the crank-arm 72, the pulley 130 being attached so that while tying a shock as the knitter turns, the crank 72 pulls on the trip stop 55 through the cable 128 and after the shock is tied and the needle starts up the trip stop 55 unlatches the machine through the double acting arm 53.

The knitter head includes a frame 138 journaling the shaft 71. Fixed to the shaft 71 is a tier wheel 54. The knitter head also includes the usual disk 82, pinion 139, and knitter hook 86, with their usual ratchet and tensions. Working in conjunction with the knitter head is a stripper arm 133 having a knife 81 fastened thereto to cut the twine and strip it from the knitter hook after the shock has been tied. The breast plate 77 bolts on the knitter frame 138 as at 137 and 137'. The top end of the breast plate 77 bolts to the under side of the binder deck as at 140 and 140'. The double acting stripper arm 133 hinges on the breast plate 77, as at 79. The tier wheel 84 has an arm 78 and the stripper arm has a bracket wing 133' to which is connected a cable 134 as at 131'. This cable extends through a pulley 135 fastened to the cross bar 20. The table continuing through the pulley, connects with the spring 136 attached to the end of the crank-arm 43 so that the stripper arm is actuated when the butt holder is tripped.

In order to prevent discharge of sheaves from the binder during operation of the shock tying and setting mechanism, the binder discharge includes a shaft 194 supported over the discharge of the deck 5 and which has a plurality of hook-like fingers 193 adapted to move into position for detaining the sheaves. The shaft 194 is operated by a lateral arm 191 thereon having a finger 192 engaged in a slot at the end of a link 190, having its opposite end attached to the crank 101 of the needle shaft. The arm 191 has a lateral extension 196 which is adapted to be engaged by an arm 195 on the discharge shaft to effect raising of the fingers 193 and allow continued discharge of sheaves into the shocker after the shocker has returned to its receiving position. I have also provided means for stopping return movement of the upender so that one or more sheaves may be discharged from the binder directly onto the ground. This is effected by a stop pin 27' which moves through the breast plate 77 and has a retracting spring 77'. The spring 77' has a link 9' connected to the binder trip 9 so that the pin is adapted to be retracted after one or two bundles have been discharged (see Fig. 16). The butt holder may also be provided with a pan 143 to prevent slipping forward of the sheaves in the shocker while the harvester is crossing ditches.

While I have described the mechanism of the machine as driven from the main wheel, it is obvious that the binder and shocker mechanisms may be driven from a power take-off of a draft vehicle by use of a flexible shaft as illustrated in Fig. 17.

195 designates a shaft adapted to be connected with the power take-off of a tractor and which is coupled by a universal joint 194 with a squared shaft 193 telescoping in a tubular shaft 192 that is connected by a universal joint 191 which may be connected with the shaft 31 (Fig. 6).

A machine constructed and assembled as described operates as follows:

The machine is connected with a suitable draft vehicle and drawn over the field, the various mechanisms being driven responsive to rotation of the main wheel or by a flexible shaft connection with the power take-off. The grain cut by the sickle falls onto the conveyor and is carried thereby to the binder deck 5 and is tied in sheaves in conventional manner, with the sheaves being discharged into the shocker so that the heads fall into the upender and the butts upon the holder 14. At the time the first sheaf is discharged the knotter trip dog 75 engages against the trip stop 87 and the upender and butt holder are held home by the trip stop 55 latchingly engaging the arm 53 as shown in Fig. 2. With the trip dog 75 engaging the stop 87, the needle shaft 100 is held in position so that the spring 111 is acting to relieve tension of the roller 108 on the twine 112, which twine is connected with the knotter hook and supported by the needle over the top of the shock upender as shown in Fig. 2. Consequently, the first sheaf strikes the twine and carries it into the shocker. When the next sheaf is discharged from the binder deck, the crank-arm 119 is pulling on the link 118 to trip the stop member 98 so that the stop 87 thereon is moved away from the trip dog 75 thus allowing the clutch to engage and move the trip dog into stopping relation with the stop 88. Since the stop member 98 has been returned to its original position, and as the link 97 holds the needle shaft in position to exert pull on the spring 111, there is no tension on the twine 112. When the second bundle is discharged, motion is again imparted to the link 118 by the crank-arm 119 to again trip the stop member 98 and shift the stop 88 away from the trip dog 75 so that the trip dog then moves against the stop 89, thus shifting the needle shaft further to the right (Fig. 10), so as to relieve pull on the spring 111 and establish tension on the twine. The tension will then remain on the twine during the completion of the shock and during tying thereof. When succeeding sheaves are deposited in the shocker, the trip stop 88 will be actuated, but at these times the trip dog 75 is contacting the stop 89 and therefore the trip dog retains its position. When a sufficient number of sheaves have been deposited in the shocker the operator will pull the cable 99 to the shift stop 89 from engagement with the trip dog 75, whereupon the trip dog is again momentarily released to engage the trip stop 88'. When the last bundle is discharged into the shocker, the stop 88' is shifted from engagement with the trip dog with the result that the clutch begins to rotate to start the tying operation.

When the tying operation starts, the needle 102 carries the string around the shock with the twine hold-down 103 retaining the string in proper position for tying and stripping of the knot from the knotter hook. Simultaneously with the actuation of the needle, the compressor 127 comes into play to compress the sheaves. As the needle starts back after the shock is tied, the crank-arm 72 pulls on the cable 128 unlatching the trip stop 155 from the double acting crank 53, letting the butt holder 14 drop the butt of the shock to the ground. When the butt holder 14 drops the shock to the ground, the butt holder crank 43 gives the stripper arm 133 another

swing through the cable connection 134 so that in case the twine has been held by the knotter hook, the extra swing will strip it therefrom. When the needle shaft 100 is actuated to move the needle downwardly, the link 190, which is attached to the needle shaft crank-arm 101, operates the crank-arm 191 to swing the shaft 194 so that the fingers 193 thereof are moved into position to hold the next sheaf to be discharged from the binder and prevent its interference with tying of the shock and hold it while the shock is being set on the ground. When the butt of the shock is dropped to the ground, the upender rocks by reason of the forward travel of the machine so that the shock is moved to a perpendicular position. When the finger 66 contacts the shock, the roller 69 moves the section 60' of the track out of position, consequently the spring 58 comes into play to move the toe 63' of the dog 63 into contact with the teeth of the clutch wheel at the time the end of the dog engages with the track. The clutch wheel is then effective to complete rotation of the upender and swing it quickly across the top of the shock so that it gets away therefrom simultaneously with forward movement of the machine. As the upender moves across its uppermost dead center position, the end 65 of the dog 63 again engages the track 60 to disconnect the high speed drive and the upender settles to its normal position. The change connection 51 simultaneously raises the butt holder 14, and the double acting crank is again latched by the trip 55. By the time another sheaf is formed and tied, the arm 195 engages the extension 106 on the arm 191 to raise the hook-like fingers 193 and allow discharge of the succeeding sheaves into the shocker. In case it is desired to drop one or two bundles on the ground for caps, the stop pin 27', which acts through the breast plate 71, is contacted by the shock upender, and the upender is held thereby until the binder has discharged one or two bundles from the binder. These bundles fall on the ground, after which the binder trip 9, through the link 9', releases the pin 27' from the shock upender, whereupon the shock upender returns to its original position ready to receive sheaves for forming another shock.

As above described, tension is off of the twine when the trip dog 75 is engaging the stops 87 and 88, and is put on the twine when the dog is engaging the stops 89 and 88', but attention is directed to the fact that the tension on the twine 55 may be removed for a greater number of bundles by the provision of more stops between the stops 87 and 89.

What I claim and desire to secure by Letters Patent is:

1. In a sheaf shocker, shock tying mechanism comprising means including a needle for looping the twine around a shock of sheaves, means including a head having a hook for cooperating with said needle to tie a knot in said twine and secure the same about the shock, means to tension said twine about said shock during the knotting operation, means movable relative to said hook for stripping each knot therefrom, means operatively connected to the knot tying means to actuate said stripping means, and separate means operatively connected to said stripping means independent of the knot tying means to cause a second stripping operation after each tying operation.

2. In harvesting apparatus having a binder, the combination comprising means for collecting sheaves to be tied into shocks, means for discharging sheaves from said binder into said collecting means, means for tying said collected sheaves into shocks, a movable control device for said tying means, means including a clutch for moving said control device and operating said tying means, means providing two stops in the path of movement of said control device, manually operable means for withdrawing one of said stops to release said control device for movement until arrested by the second of said stops, and means operated from said binder discharge means for retracting said second stop to release said control device for initiating a tying operation.
3. In a harvesting apparatus including means for forming cut grain into sheaves, a shocker mechanism, means movably carrying the shocker mechanism in receiving relation with said sheaf forming means, actuator means for effecting movement of the shocker mechanism from receiving position relatively to the sheaf forming means to shock setting position, means between the sheaf forming means and the shocker mechanism for detaining a formed sheaf while a succeeding sheaf is being formed and while the shocker mechanism is moved from shock setting to sheaf receiving position, means acting in timed relation with the sheaf forming means for releasing the detaining means to discharge formed sheaves into the shocker mechanism, means associated with the shocker mechanism for projecting and tying a twine about the sheaves in the shocker mechanism, and means having connection between said last named means and the sheaf detaining means to operate said detaining means and prevent discharge of a sheaf during tying of a twine about the sheaves in the shocker mechanism.
4. In a harvesting apparatus including means for forming cut grain into sheaves and a trip in the path of sheaves discharged from the sheaf forming means, a shocker including an upender, means movably carrying the upender in receiving relation with the sheaf forming means, actuating means for effecting movement of the upender from receiving relation relatively to the sheaf forming means to shock setting position, latch means carried by the shocker in the path of the upender to detain movement of the upender from shock setting position to sheaf receiving position while a capping sheaf is discharged from the sheaf forming means, means connecting the trip with said latch means to effect release of the upender after deposit of the capping sheaf so that the upender returns to position for receiving succeeding sheaves, means carried by the shocker for projecting a twine about the sheaves in the shocker, cooperative means carried by the shocker for tying a knot in the twine, and sheaf detaining means having operative connection with the twine projecting means for detaining sheaves in the sheaf forming means during the projecting and tying of the twine.
5. In a harvesting apparatus including means for forming cut grain into sheaves, a shocker mechanism, means supporting the shocker mechanism in receiving relation with the sheaf forming means and movable to shock setting position, means acting in cooperation with the sheaf forming means for discharging the sheaves into the shocker mechanism, means carried by the shocker mechanism for tying a twine about the sheaves to form a shock, actuating means for the shocker mechanism to deposit a tied shock on the ground including means for returning the shocker mechanism to receiving relation with the shock forming means, means movably supported in the path of the discharged sheaves for selectively detaining formed sheaves in the sheaf forming means during actuation of said tying means, and means having releasable connection with said discharge means for interrupting movement of the shocker mechanism to receiving position whereby a detained sheaf is dropped on the ground.
6. In a harvesting apparatus including means forming cut grain into sheaves, a shocker, means carrying the shocker in receiving relation with the sheaf forming means whereby formed sheaves are individually discharged into the shocker, means movable across the shocker for projecting a twine about the sheaves in the shocker, a knotter head on the shocker, a knotter hook cooperating with the knotter head for tying a knot in the twine, stripping means having operative connection with the twine projecting means for cutting the twine and stripping the knot from the knotter hook, actuating means for the shocker to set the shock in upright position, a secondary stripping means adapted to strip the knot from the knotter head in case of failure of the first named stripping means, and an actuating connection between said secondary stripping means and the shocker for actuating said secondary stripping means incidental to actuation of the shocker.
7. In a harvesting apparatus including means for forming cut grain into sheaves, a shocker, means carrying the shocker in receiving relation with the sheaf forming means whereby the formed sheaves are individually discharged into the shocker, a needle having support for movement across the shocker to draw twine about the sheaves in the shocker, a knotter head on the shocker in line with the path of the needle, a knotter hook cooperating with the knotter head for tying a knot in the twine, means actuated responsive to movement of said twine drawing means for cutting the twine and stripping the knot from the knotter hook, actuating means for the shocker to set the shock in upright position, and a secondary stripper actuating means adapted to strip the knot from the knotter head in case of failure of the first named stripping means, said secondary stripper actuating means having connection with the shocker whereby said secondary stripping means is effected incidental to actuation of the shocker.
8. In a harvesting apparatus including sheaf forming means, a shocker, means acting in cooperation with the sheaf forming means for delivering sheaves into the shocker, means on the shocker for projecting and tying a twine about the sheaves to form a shock, a trip on the shocker having a plurality of stops, said trip being actuated by said sheaf delivering means, a trip clutch for operating said tying means including a trip dog successively engageable with said stops, a twine tensioner on the shocker, and means connecting the tensioner with said twine projecting and tying means whereby tension is released when the trip dog is engaging selected stops.
9. In a harvesting apparatus including sheaf forming mechanism, a shocker supported in receiving relation with said sheaf forming mechanism, sheaf detaining means controlling discharge of sheaves from the sheaf forming mechanism

- and acting in timed relation with said sheaf forming mechanism to detain a formed sheaf while a succeeding sheaf is being formed, means supporting a binder twine across the shocker, tension mechanism engaging the twine, means actuated responsive to discharge of a sheaf from the sheaf forming mechanism and having connection with the detaining means for initially releasing tension on the twine so that the sheaves 5 move the twine therewith into the shocker, means for retaining said detaining means ineffective during formation of succeeding sheaves whereby the succeeding sheaves are individually discharged into the shocker, and means for projecting and tying the tension twine about the sheaves in the shocker.

10. In a harvesting apparatus including means for forming cut grain into sheaves, a shocker including a shock upender and a butt holder pivotally supported in receiving relation with the sheaf forming means, means for projecting a 5 twine about sheaves in the shocker, a knotter head on the shocker, a knotter hook cooperating with the knotter head for tying a knot in the twine, stripping means actuated responsive to movement of said twine projecting means for cutting the 10 twine and stripping the knot from the knotter hook, and an operating connection between the butt holder and said stripping means responsive to movement of the butt holder to assure stripping of said knot from the knotter hook. 15

JAMES A. McELROY.
